Displays, Inc., New York, N.Y.

Filed Jan. 8, 1973, Ser. No. 321,567

Term of patent 14 years

Int. Cl. D20—02; D6—04

U.S. Cl. D6—186

FIG. 1 is a front perspective view of a modular display case for fabrics or the like, embodying my new design;

FIG. 2 is a top plan view thereof;

FIG. 3 is a front elevation view thereof, the rear view being the mirror image of FIG. 3;

FIG. 4 is a vertical transverse section view, taken along the line 4—4 of FIG. 1;

FIG. 5 is a front perspective view of a modified form of the modular display case;

FIG. 6 is a top plan view of the modified form; and

FIG. 7 is a front elevation view of the modified form, the rear view being the mirror image thereof.

The bottom of the display rack is plain.

I claim:

The ornamental design for a modular display case for fabrics or the like, as shown and described.
